METHOD OF CASTING TETRAHEDRONS

Application filed June 8, 1931. Serial No. 542,826.

Skeleton tetrahedrons for use for the purpose set forth must be massive and strong and are made of a metallic framework on which concrete is molded to form the corners and beams or legs.

There are various objections to building such structures at the places where they are to be used, as they may be manufactured there only by massing of expensive forms, material and labor. Experience shows this work can be performed at a central plant or station where exact materials for the making of same can be procured and a better grade of concrete be properly cured in the yard; but owing to the great weight and unshippable size of most of these complete figures it is impracticable to make them complete at a central plant.

An object of this invention is to provide a practical skeleton tetrahedron adapted for manufacture in separate parts that may be transported independent of each other to the place of use, and to make provision whereby such parts may be readily assembled and fastened together at the place of use, and thereby made into integral units.

Another object is to provide a precast tetrahedron formed of permanent materials, which is adapted to quickly become anchored in the stream bed under the erosive and depositing action of the water without disintegration, a device which may become displaced without impairing the stream bank, and to slow down the water sufficiently adjacent to the bank and bottom to insure the collection of silt and detritus against the same and the remainder of the stream being allowed to flow on unimpeded.

Experience in the use has shown in order to prevent the units from being carried away, the end ones or those that are exposed to heavy current action must be strongly fastened together so as to make a flexible unit of the row of figures that they may readily conform to the irregularities of current action.

Another object of the invention is to secure maximum strength in a composite reinforced concrete precast skeleton tetrahedron and particularly to strengthen the corner pieces,

and dispose the parts to maximum advantages of anchoring efficiency.

Other objects, advantages and features of invention may appear from the accompanying drawings, the subjoined detailed description and the appended claim.

The accompanying drawings illustrate the invention.

Figure 1 is a plan view on a small scale of a stream or river in which is shown a series of skeleton tetrahedrons placed in a desired position from one of the river banks and also shows a cable fastening each tetrahedron together to form a flexible row of figures. Arrows denote the direction of the river flow.

Fig. 2 is a side view of a skeleton tetrahedron shown embedded in the river bottom with the water flowing in the direction of the arrow.

Fig. 3 is an enlarged fragmental face view of a precast leg.

Fig. 4 is a side elevation of Fig. 3.

Fig. 5 is a detail plan view showing the connection of three leg sections.

Fig. 6 is an enlarged fragmental detail showing one of the bolt connections.

Fig. 7 is an enlarged front elevational fragmental detail view showing another type of loop used to keep the cable in contact with a leg of the tetrahedron.

Fig. 8 is a plan view of Fig. 7.

Fig. 9 is a plan view of a skeleton tetrahedron forming a unit constructed in accordance with this invention.

Fig. 10 is a side view of the same on a smaller scale.

Fig. 11 is a front view.

Fig. 12 is an enlarged side view of the steel frame of a leg section.

Fig. 13 is an end view of Fig. 12.

Fig. 14 is a top view of one of the leg sections.

Fig. 15 is an enlarged section on line X15 Fig. 14.

Fig. 16 is a side view of Fig. 14.

Fig. 17 is a bottom plan view of Fig. 16.

The skeleton tetrahedron is composed of six leg sections 1, which are alike, and twelve joints 2, which are alike, connecting the leg sections to each other.

The leg sections 1 are provided with reinforcing rods *a*, *b*, *c*, *d* and *e* having straight bodies 3 and rods *a*, *b* and *c* have terminal loops or bends 4 that project from the faces 5 of the ends of the leg members. The loops at the ends of the leg sections are alike and are adapted and arranged to be juxtaposed to receive the pins 6 which are preferably in the form of bolts having a taper end 7 and 10 a slot 8 into which a tapered key 9 is fitted against a washer 10 to hold the pairs of juxtaposed loops together.

Tie wires 11 are preferably positioned along the frame work of the reinforcement rods to 15 hold the latter in proper adjustment.

The terminal loops are economically made by bending the rod terminals to form a **U** bend, the base of which will protrude beyond the ends of the leg section and are staggered 20 as shown in Fig. 5, to allow the constructor to insert the pins 6 through the loops and make them secure before filling the triangular gap with concrete or other cementitious material to complete the reinforced joint.

25 The body of the rod beyond the base of the loop is of sufficient length to be embedded in the body of the leg section as the case may be when the same is molded at the place of manufacture.

30 Referring to Fig. 1 the method shows a row of tetrahedrons placed in position from one of the river banks, and fastened by a cable 12 that may be anchored at 13 to the bank.

35 The cable 12 is shown slidably fixed to the front legs of each tetrahedron by the loops 14 and is fastened to the end unit as at 15. This arrangement or method of fastening each tetrahedron by a cable to form a flexible 40 row of figures that may readily conform to the irregularities of the current flow of the stream may be carried out in other forms of construction and there is no limit as to the number of units or cables or type of loops 45 that may be used without departing from the spirit of my invention.

I claim:—

The method of producing reinforced concrete tetrahedrons adapted for service in establishing and maintaining river banks in 50 and with alluvial soil deposits, wherein the tetrahedron sides are angular and of skeleton formation with the skeleton legs arranged to complete the side configuration, said method 55 consisting in precasting the legs individually with enlarged ends and with reinforcing elements exposed at the ends of the leg, producing the embryo tetrahedron by assembling the respective legs into the tetrahedron form 60 with the exposed reinforcing elements at an end of a leg positioned relative to those of an adjacent leg to permit the elements to be secured together to anchor the legs relatively with the anchor elements exposed, and then 65 completing the tetrahedron by the addition

of concrete to fill the spaces formed at the corner angles during the assembly and encase the exposed anchor elements, whereby the angular corners will be continuous and of reinforced concrete formation of which the leg reinforcing elements are an integral part to anchor the sides relative to each other.

In testimony whereof, I have hereunto set my hand at Los Angeles, California, this 28th day of May, 1931.

DANIEL F. SHELDON.
